COMBINATION MIRROR AND CLOCK

Norman En Holm, New York, N. Y., assignor to
 Multi Vue Sign Co., Inc., a corporation of New
 York

Application October 19, 1937, Serial No. 169,762

11 Claims. (Cl. 272—13)

This invention relates to a combination mirror and clock which may be used for advertising or other purposes.

An object of the invention is to produce a device of the character described having a front mirror which may be used as a mirror per se by persons standing in front thereof, said mirror having combined therewith a clock the face of which when illuminated appears to view in 10 place of the aforesaid mirror.

Another object is to produce a device of the character described wherein the front mirror is translucent and one or both mirrors are movable whereby certain moving effects of indicia located 15 within the device or indicia projected thereon, are obtained.

A further object is to produce a device of the character described wherein the hands of a clock are located in front of the mirrors therein while 20 the clock face numerals are located (either with or without accompanying indicia such as advertising data or the like) on one of the mirrors or the indicia is projected thereon.

Other objects of the invention will be apparent from a perusal of the following specification and include the object of producing a device of the character described in which multiple images of the indicia comprising a sign or clock face are produced and if desired said multiple images are 25 caused to move.

It will be understood that modifications, variations and adaptations may be made in the device herein shown and described by way of illustration, without, however, departing from the appended claims.

By way of illustration there is shown and described herein a device that may be used for advertising purposes comprising a casing having its front closed by a translucent mirror having a second mirror which need not be translucent in the rear thereof. Before the first or outer mirror are positioned the hands of the clock, the numerals for the clock face being placed on the second or rear mirror, or these numerals may be 40 projected on to the device or reflected thereby in a manner hereinafter described.

With the device illuminated by ordinary light from the front, such for example as when the device is located in a store window and illuminated by ordinary daylight, the front of the device would present a smooth, unbroken mirror-like surface except for the clock hands. Then by illuminating the rear mirror the outer mirror being translucent apparently disappears from view 45 and the numerals of the clock dial appear and

because the two mirrors are spaced apart, repetitive reflections occur so that apparently these numerals go marching off into infinity in a manner well known in connection with reflecting signs of this character.

If one or both of the mirrors are moved, then the repetitive reflective images also move and a large number and variety of combinations of one or both moving mirrors can be effected to produce various attractive effects. Some of these 10 constructions are given in the copending applications, Serial Nos. 152,698, 152,699 and 152,700, all filed July 9, 1937.

It will also be understood that sign indicia may be placed on any one of the surfaces of either 15 mirror. When placed on the mirror surface, the indicia is usually placed on the rear surface of the rear mirror, the opaque silver coating thereon being removed and the indicia placed on the clear glass using translucent colors. If the sil- 20 vering is removed from the rear of the rear mirror and the indicia is painted in translucent colors on the front of the rear mirror and the sign is illuminated from the back, the letters ap- 25 parently swing out surrounded by a halo or radiation of light due to the passage of light through the glass of the rear mirror, which light finds its way around the indicia. It will be understood 30 it is immaterial in so far as the carrying out of this invention is concerned, as to where the in- 35 dicia is placed and in this connection reference is had to the aforesaid application, Serial No. 152,698, in which the device proper does not contain any indicia at all or may contain part of the indicia and the image of indicia, such for example 40 as a bottle, a package of cigarettes or other merchandise, is caused to fall on the sign to cause a primary image thereon by putting the merchandise in front of the device and strongly illuminating the merchandise, a reflected image of 45 which is produced in the device, the mirrors therein cooperating to produce a plurality of images, which images may be caused to move by moving the mirrors in the device.

Another method of applying the indicia to the 45 device is to direct a beam of light on to the device from a stereopticon or the like in which is a slide bearing the indicia. When the light beam strikes the device, the mirrors pick up the indicia projected thereon and operate as heretofore de- 50 scribed.

It will be seen from the foregoing that it is immaterial where the indicia is placed on the mirrors or projected or reflected thereon. For portable devices it is preferable to put the indicia on 55

the back mirror and illuminate the same from means such as electric lamps contained in the casing of the device.

Referring now to the drawing in which is illustrated a device of the character described comprising a combination sign and clock:

Figure 1 is a plan view, partly in section, of a device in which both of the mirrors are movable;

Figure 2 is a plan view, partly in section, of a device in which both of the mirrors are fixed;

Figure 3 is a front elevation of the sign shown in Figure 1, as seen with rear illumination; and

Figure 4 is a sectional plan view on the line 4-4 of Figure 3 showing the attachment of the 15 clock hands to their driving shafts.

Referring to Figure 1 which is typical of any type of construction in which one or both of the mirrors are movable, the numeral 10 denotes a front casing in which is supported a plain glass 20 front 11 which front, however, may in some instances be dispensed with. The casing 10 is provided with a door 12 on its side or in its top to permit removal of the mirrors which may be supported in a suitable framework, as more fully described in copending application Serial No. 25 169,761, filed October 19, 1937.

The outer mirror 13 and rear mirror 14 are mounted to oscillate or swing about the vertical axis 15, the front mirror 13 being translucent and 30 the rear mirror 14 being opaque except when it carries indicia, in which case the silvering is removed from the glass and the indicia placed thereon using translucent colors.

The mirrors 13 and 14 are apertured at their 35 center, as more clearly shown in Figure 4 to permit the mechanism for driving the clock hands to pass therethrough. This mechanism may be of any suitable form, may comprise the usual hour and minute hand shafts generally denoted in Figures 1 and 2 by the numeral 16, which shafts are connected through any suitable gearing to shafts 17 which are driven by a clock mechanism 18.

The clock mechanism 18 is disposed to one side 40 of the mirrors so as to be out of the way in the event that the mirrors are illuminated from the rear, as hereinafter referred to, and the shafts 17 and the associated parts 16 are also made as small as possible so as not to cause any shadows in the event of rear illumination.

If desired, the mechanism 18 may comprise any 45 suitable form of spring or electric motor. If the latter is used, it may be any of the known types of such motors which commonly have an armature shaft which, through appropriate gearing drives the shafts 17 to operate the hands of the clock. Such motors may be, and commonly are, equipped with auxiliary gearing, which may be connected to the crank arm 19 one end of which is connected to the motor gearing and the other end of which connects to the mirrors 13 and 14 50 so that, when the motor mechanism 18 is in operation, the crank 19 connected thereto will move the mirrors as shown in dotted lines, Figure 1. From this it will be apparent that one motor device 18 may be used to operate the clock and also move the mirrors.

The motor 18 is connected to a source of current supplied via the wires 20 which also connect to means for illuminating the mirrors comprising the lamps 21 and 22. The rear casing 23 encloses and surrounds all of the parts being connected in any suitable manner to the front casing 10.

The clock hands 24, 25 are provided with 75 shouldered slip sockets or the like as indicated at

26, Figure 4, so that these hands may be secured to and removed from the shafts 16 from the front of the device. This is accomplished by sliding the glass front 11 out of the casing 10, then removing the hands. This permits the withdrawal of the 5 mirrors 13 and 14 through the door 12 in the casing 10 or through a similar door (not shown) in the top of the casing. Without this provision for detaching the hands it would be necessary to open the rear of the device and disassemble the 10 driving shafts 16 from the clock mechanism.

The numerals for the clock face may be placed on the rear mirror 14 as previously described, and the device being as shown in Figures 1 and 3, if looked at from the front without lamps 21 and 22 15 being lit, will have the effect of an ordinary plain mirror except that the clock hands 24 and 25 will be visible but an observer standing in front of the device would see himself reflected in the front mirror 13, and the clock numerals shown in dotted 20 lines, in Figure 3, would not be visible.

The lamps 21 and 22 being illuminated, the on-looker would now see the numerals on the clock face, but would not see his own image, as the front of the device, that is to say the front mirror, 25 would apparently become transparent, and if motor 18 was in operation the clock face numerals and any other indicia forming the sign on the rear mirror 14 would apparently move in long 30 lines out into infinity.

The operation of the sign, Figure 2, is substantially the same as that just described, except that here the mirrors 13 and 14 are stationary within the casing. The effect is obtained of repetitive 35 multiple reflections which will apparently move as the observer moves in front of the sign, that is to say the long lines of repetitive images moving off into infinity will apparently shift their position as the observer moves in front of the sign. However, if the observer remains perfectly 40 still these images will not move in the sense that the images referred to in connection with the sign, Figure 1, move.

Assuming by way of illustration that an observer stands in front of the sign, Figure 1, holding a lighted match in his hand, this sign will 45 show the flame image reflected several times and, as the mirrors move, this image will swing backwards and forwards and this will happen without lamps 21, 22 being lit, and without any indicia 50 whatever appearing on the sign.

If the observer repeats the foregoing in connection with sign No. 2, the flame image will be re-reflected several times but will not move except to the extent that the match is moved by 55 the observer.

In connection with either sign Figure 1 or Figure 2, floodlighting the sign from the front shows the indicia, if any, on the back mirror, re-reflected several times, and in the same manner as if the lamps 21, 22 were lighted.

If some object such as a bottle is placed in front of the signs, Figures 1 and 2, and floodlighted, the bottle image is re-reflected several times, or if a picture is projected on to the front 65 of either sign, Figure 1 or 2, re-reflected images will be produced.

What is claimed is:

1. In a device of the character described, a casing, a pair of relatively fixed mirrors movably 70 mounted therein, the outer of said mirrors being translucent and the rear mirror being opaque and having translucent indicia thereon, said outer mirror being positioned in the front of said casing and both said mirrors being apertured, 75

clock mechanism mounted in said casing and including means for driving the hands of the clock extending through said apertures in said mirrors, clock hands secured to said means and positioned 5 in front of said outer mirror, means for illuminating said mirrors to form multiple images of indicia reflected thereby, and means for moving said mirrors.

2. The device as claimed in claim 1 wherein the 10 means for illuminating the mirrors is located behind said rear mirror, which has translucent indicia thereon through which light may pass to cause said indicia to be reflected by said outer mirror.

15 3. In a device of the character described, a casing, a pair of relatively fixed mirrors mounted in said casing and spaced apart from each other, the outer of said mirrors being translucent and the rear mirror being opaque and having translucent 20 indicia thereon, said outer mirror being positioned in the front of said casing and both said mirrors being apertured, clock mechanism mounted in said casing and including means for driving the hands of the clock extending through said 25 apertures in said mirrors, clock hands secured to said means and positioned in front of said outer mirror, means for illuminating said mirrors, to form multiple images of indicia reflected thereby, and means for moving said mirrors.

30 4. The device as claimed in claim 3 wherein the means for illuminating the mirrors is located behind said rear mirror, which has translucent indicia thereon through which light may pass to cause said indicia to be reflected by said outer 35 mirror.

5. In a device of the class described, a casing, a translucent outer mirror fixed therein having clock face indicia thereon normally visible from the front thereof, a rear mirror fixedly positioned 40 in said casing behind said translucent mirror, both said mirrors being apertured, clock mechanism mounted in said casing and including means for driving the hands of the clock extending through said apertures in said mirrors, clock 45 hands secured to said means and positioned in front of said outer mirror, and means for illuminating said mirrors to form multiple images of indicia reflected thereby.

6. The device as claimed in claim 5 wherein 50 said mirrors are relatively fixed together and movably mounted as a unit in said casing.

7. In a device of the character described, a casing having therein a front translucent mirror and a rear mirror, said mirrors being apertured, clock mechanism supported in said casing behind said mirrors and including shafts for driving the 5 clock hands, clock hands supported on said shafts having extension members projecting through said apertures in said mirrors and adapted for engagement with said shafts, and means for illuminating said mirrors. 10

8. A device as claimed in claim 7 wherein said extension members are in frictional engagement with said shafts whereby said hands may be removed from the front of the device to permit withdrawal of said mirrors therefrom. 15

9. In a device of the character described, a casing having a translucent mirror in the front thereof and a rear mirror behind said translucent mirror and adapted to produce therewith multiple reflections, said rear mirror carrying 20 numerals or the like forming a clock dial or face, said mirrors being apertured, clock hand driving mechanism passing through said apertures said mechanism being located within said casing, and clock hands overlying the face of said translucent mirror and connected to said mechanism. 25

10. In a sign of the character described, a pair of apertured mirrors one of which is translucent, said mirrors adapted to produce multiple reflections, and a clock movement positioned behind 30 said mirrors and having a shaft extending outwardly through said apertures therein, hands on said shaft, and clock-face indicia on one of said mirrors.

11. In a device of the class described, a casing, a translucent outer mirror fixed therein normally visible from the front thereof, a rear mirror having indicia and being translucent whereby light may pass therethrough to cause said indicia to be reflected by said outer mirror, said rear mirror being fixedly positioned in said casing behind said translucent mirror, both said mirrors being apertured, clock mechanism mounted in said casing and including means for driving the hands of the clock extending through said apertures in said mirrors, clock-hands secured to said means and positioned in front of said outer mirror, and means for illuminating said mirrors to form multiple images of indicia reflected thereby.

NORMAN EN HOLM.
